IMPACT ATTACHMENT FOR WHEEL LUG WRENCHES

Filed May 31, 1949

UNITED STATES PATENT OFFICE

2,600,796

IMPACT ATTACHMENT FOR WHEEL
LUG WRENCHES

Paul H. Nash, White Deer, Tex.

Application May 31, 1949, Serial No. 96,202

4 Claims. (Cl. 81—52.3)

1

This invention relates to automobile wheel lug wrenches and more particularly to an attachment for such wrenches adapted to create through impact, a force on the lug wrench effective to loosen the most obstinate lug nut and, conversely, to tighten the same.

The principal object of the invention is to provide an impact imposing attachment for a lug wrench of the type having radial socket arms and employed chiefly for mounting and demounting tires of heavy duty hauling equipment, buses, tractors and the like having oversized lugs and retaining nuts and bolts. The attachment consists of a pin adapted for insertion in the center-hole of the lug wrench and to which is pivoted an arm carrying a hammer on its outer end adapted to be brought forcibly against one or the other of the sockets on the wrench arm at right angles to the arm carrying the lug socket being applied and thus to impose on the operative arm an impact effective to create a starting torque to loosen a lug nut or to tighten the same as the case may be.

Another object of the invention is to provide an impact attachment for lug wrenches in which the pivot pin to which the impact arm is attached is replaceable in the center-hole of the lug wrench in at least two positions in order that the impact arm may be disposed in parallelism with selected arms of the wrench, thus to permit the hammer to be brought into engagement with the respective sockets of the wrench arm. Provision is made to prohibit rotative displacement of the mounting pin of the attachment to insure alignment of the impact arm with a selected socket arm of the wrench at all times.

With the foregoing objects in view, the invention has further reference to certain features of accomplishment which will become apparent as the description proceeds, taken in connection with the accompanying drawings wherein:

Figure 1 is a perspective view of a conventional lug wrench, except for the provision of a slotted center hole.

Figure 2 is a fragmentary elevational view of a lug wrench having a square center hole.

Figure 3 is a fragmentary perspective view of the impact attachment illustrating the form of mounting pin applicable to the form of lug wrench shown in Figure 1.

Figure 4 is a fragmentary elevational view of the lug wrench shown in Figure 2, partly in section and showing the impact attachment of the invention installed thereon.

Figure 5 is a fragmentary sectional view of the lug wrench showing the mounting pin locking key, and

Figure 6 is another modification of an attaching means for the impact arm to conventional lug wrenches which are without a center hole.

2

Continuing with a more detailed description of the drawing, reference numeral 10 denotes generally the lug wrench which, except for the grooved center hole 11, is of conventional manufacture. Further reference to the grooved hole 11 will be made presently.

The lug nuts on heavy duty vehicle wheels become firmly set, especially after being long exposed to road slush and frequently require a starting torque to loosen them on their bolts. The most effective force is by sudden impact as by a jarring blow imposed in a direction tending to rotate the wrench arm carrying the nut socket being applied.

The present invention therefore provides an impact attachment consisting of an impact arm 12 having a bifurcated end 13 while on the opposite end of the arm is formed or attached a weighted head or hammer 14. An axial extension 15 is formed on the head 14 and carries a form of handle 16 which may be of any suitable shape and which adds to the effective weight of the head.

Pivoted in the bifurcated end of the impact arm 12, by means of a bolt 17 is the shank 18 of a mounting pin 19. In Figure 1 the pin 19 is of slightly different form than shown in Figures 3, 4 and 5, the same being cylindrical in shape rather than square as illustrated in the latter views. However, the principle is identical hence the same reference numerals are employed to indicate like parts in the several views.

The purpose in making the pin 19 cylindrical is to accommodate the same to the circular hole 11 of the wrench 10 which is present in the conventional wrench and all that is necessary to adapt the attachment to the wrench is to produce two slots 20 in the wall of the hole approximately 90° apart. Conforming to one or the other of the slots 20 is a key 21 formed on the shank 18 of the pin 19. When the pin 19 is disposed so that its key 21 is in one slot 20, the impact arm 12 will lie parallel with one or the other of the radial arms 22 of the wrench. By removing and replacing the pin 19 to engage its key with the companion slot 20, the impact arm 12 of the attachment will lie parallel with one or the other of the companion radial arms 23 of the wrench.

The described arrangement is such that the handle 16 may be grasped with one hand and while holding the wrench 10 with the other to maintain a selected nut socket 24 in engagement with a lug nut, the hammer 14 on the impact arm 12 is brought into sudden contact with a socket 24 on the wrench arm which is at right angles to the arm carrying the work engaging socket, thus imposing a force tending to either dislodge an obstinate nut or to tighten the same,

depending on whether the nut is being applied or removed.

As a means to hold the pin 19 in the center hole 11 of the wrench, a longitudinal slot 25 is made in the pin which extends partially into the shank portion thereof. The end of the slot 25 nearest the end of the pin has a hump 26 (Figs. 4 and 5) therein against which rockingly bears a tapered key 27, the latter being adapted for insertion through the slot 25 to engage the spider 28 of the wrench and to draw the shank 18 of the pin well into the center hole 11. The hump 26 in the slot 25 reduces frictional contact between the key and pin and the shoulder 29 affords a stop to insure free movement of the bifurcated end 13 of the impact arm 12 when the latter is oscillated as suggested by the broken line in Figure 4 which intersects the pivotal point of the arm 12. The key 27 is suspended from the pivot bolt 17 of the arm 12 by means of a chain 30 to preclude loss or displacement of the key.

In Figures 2 to 5, the spider 28 is shown as having a square center hole 11 which obviates the necessity for slotting the circular hole. The only change necessary to adapt the mounting pin 19 to the square hole is to make the shank 18 thereof of corresponding square shape in transverse section.

To change the attachment in the form last described from a tightening position to a loosening position or vice versa it is necessary only to remove the key 27 from the slot 25, withdraw the pin from the hole and replace it after rotating it 90°.

In cases where the lug wrench does not have a center hole therein, a clamp or attaching means for the impact arm such as shown on a reduced scale in Figure 6 is employed. This clamp consists of a preferably cast body 31 having side and end flanges 32, each of which is arcuately recessed at α to receive the radial arms of the wrench 33, shown fragmentarily and in dotted lines. The center boss of the wrench is covered by one end of the body 31 and rising from the body in centered relationship with the wrench boss is a pin 34 having diametrically opposed flats to receive the bifurcated end 35 of the impact arm 36, fragmentarily shown and which is pivoted to the pin 34 at b .

Parallel extensions 37 are formed on the body 31 to straddle the wrench arm on which the body is longitudinally disposed. These extensions have longitudinal slots in register, one with the other to receive a tapered key 38, attached to the body by a chain 39. The key extends across the wrench arm opposite the body 31 and by virtue of the taper on the key, the latter may be driven into the slots of the extensions 37 a depth sufficient to firmly clamp the body onto the wrench.

When the body 31 is positioned as described, the hammer, not shown, formed on the outer end of the arm 36 may be oscillated on the pivot a and brought forcibly against the outer end of the wrench arm which is at right angles to the arm in axial alignment with the work and thus exert the added force necessary to loosen or tighten a lug nut. It is apparent also that the position of the body on the wrench may be changed to act on another arm simply by removing the key 38 and turning the body 31 90°, after which the key 38 is reinserted in the slots of the extensions 37.

Manifestly, the construction as shown and described is capable of some modification and such modification as may be construed to fall within

the scope and meaning of the appended claims is also considered to be within the spirit and intent of the invention.

What is claimed is:

- 5 1. An attachment for a cross-arm lug wrench, comprising a body adapted to rest on the intersection of the wrench arms, having end and side flanges recessed to receive said wrench arms, relatively parallel extensions formed on one of said flanges adapted to straddle a selected arm of said wrench, said extensions having longitudinal slots in register, a tapered key slidable in said slots to secure said body to said wrench, a pin in the center of said body, an arm pivoted at one end to said pin and held thereby against other than oscillative displacement in a plane parallel with the longitudinal axis of a selected arm of said wrench, and an impact head on the opposite end of said arm adapted to be brought into forcible engagement with the outer end of said selected wrench arm.
- 10 2. An impact attachment for a cross-arm lug wrench comprising a clamp adapted to be removably secured to one side of said wrench at the intersection of its arms and having a pin extending outwardly from its center, parallel extensions on said clamp adapted to straddle one of the arms of said wrench and having aligned longitudinal slots, a tapered key receivable in the slots of said extensions on the opposite side of said wrench to hold said clamp in fixed relationship with said wrench, an impact arm pivoted to said pin for oscillative displacement relative to a selected arm of said wrench and adapted to be brought into forcible engagement adjacent its outer end with the outer end of said selected wrench arm and means on the outer end of said impact arm for actuating the same.
- 15 3. An impact attachment for a lug wrench of the radial arm type, including an impact arm adapted to be disposed normally in parallelism with a selected arm of said wrench, a mounting for said arm comprising a body detachably secured to the center of the spider of said wrench and provided with a centrally disposed pin to which the inner end of said impact arm is pivotally attached, a slotted extension integral with said body, a tapered key extending through said slotted extension to draw said body firmly against said wrench spider, a hammer on the outer end of said impact arm and means carried by said impact arm for actuating the hammer thereof against the nut socket of a selected arm of said wrench.
- 20 4. An attachment for a lug wrench as set forth in claim 3 in which the slotted extension and pin provision is made to secure said body against rotation on said wrench to hold said impact arm against other than oscillative displacement in a plane at right angles to the axis of said lug wrench.
